EDWARD P. CURTISS AND HOMER H. HENDEE, OF BUFFALO, NEW YORK.

Letters Patent No. 86,820, dated February 9, 1869

IMPROVED MODE OF CONSTRUCTING BED-LOUNGES.

The Schedule referred to in these Letters Patent and making part of the same.

To all whom it may concern:

Be it known that we, EDWARD P. CURTISS and HOMER H. HENDEE, have invented a new and improved Mode of Constructing Bed-Lounges; and we do hereby declare that the following is a true and exact description thereof, reference being had to the accompanying drawings, and to the letters and figures of reference marked thereon.

Our improvements relate to that class of bed-lounges which fold together, so as to present the appearance, and be used for the ordinary purposes of a lounge during the day, and unfold when required at night, to form a bed of double the width of the lounge.

The invention consists in hinging the lounge-back and unfolding seat upon the same side of the lounge-frame, when the hinge of the back is located sufficiently below that of the seat to enable it to rest by its upper edge upon the floor, and support the unfolding part of the seat in the same plane with the stationary part thereof.

In the drawings—

Figure I is a vertical longitudinal section of our improved article of furniture, when folded together as a lounge.

Figure II is a rear view of the same, with the back removed.

Figure III is a cross-section of the lounge, with the same shown in red lines unfolded, forming a bed.

Figure IV is a perspective view of the head-portion of the bed.

Like letters refer to like parts in each of the figures. A is the back of the lounge, hinged at *i* to the lower or main portion E of the frame, as shown, (Fig. III.)

B is the stationary portion of the arm of the lounge, which is attached to the frame E.

D is the upper and movable portion of the frame, hinged at the back side to the main frame, as shown at *x*, Fig. II; and

C, the corresponding portion of the arm, which is hinged to the frame D at *e*.

The stationary portion of the bed, within the frame E, is provided with spiral springs *m* *m*, which rest on the bottom slats L L.

The upper portion of the seat, or the hinged portion

of the bed within the frame D, is provided with spiral springs N N, of the form shown, which are inserted in pieces of webbing, K K, so as to project equally on each side, and be in the same relative position as the lower springs *m*. This webbing is secured at the ends to the frame, in any suitable manner.

P represent any suitable material for covering the springs, on both sides of the upper portion and the top of the lower portion of the seat or bed.

When used for a lounge, the two portions of the frame may be secured together by bolts or catches, as shown at *a* *a*.

The portion A, when employed as a back for the lounge, is secured in place by two hooks, one connecting with the arm at the head, and the other with the frame at the foot, though any other suitable means for the purpose may be employed.

The operation of our improvements is as follows:

Arranged as a lounge, each pair of the springs *m* N, being one above the other, forms, in effect, but a single spring, and is of great elasticity, possessing double that of a single spring. The webbing K secures the springs N in place, and at the same time yields sufficiently to permit the free action of the whole spring, whether used on the lounge or for the bed.

To convert the lounge into a bed, the back, A, is first let down, (shown in red lines, Fig. III,) when the upper portions C D of the arm and frame are released and turned back, the latter resting on the back, A, and the arm C arranged (which its hinges *e* permit) so as to form an extension of the stationary part B of the arm, any suitable stop, *s* *s*, being employed to retain the former in its proper inclined position, in line with the latter.

What we claim as our invention, and desire to secure by Letters Patent, is—

Hinging the lounge-back A upon the same side with the unfolding part D of the seat, and below the same, so as to operate substantially as herein set forth.

EDWARD P. CURTISS.
HOMER H. HENDEE.
